CARRYING CASE FOR PORTABLE HAIR DRYER OR THE LIKE

Ivar Jepson and Robert O. Ernest, both of Oak Park, Ill., assignors to Sunbeam Corporation, Chicago, Ill., a corporation of Illinois

Filed Dec. 11, 1961, Ser. No. 67,866

Term of patent 14 years

(Cl. D87—5)

FIG. 1 is a perspective view of a carrying case for portable hair dryer or the like showing our new design;

FIG. 2 is a front elevational view thereof;

FIG. 3 is a side elevational view thereof; and

FIG. 4 is an enlarged scale sectional view taken on line 4-4 of FIG. 2.

The bottom is the same in appearance as the top except for the provision of three legs as shown in FIGS. 2 and 3.

The dominant features of our design reside in a contrasting band, having corrugations as shown in FIG. 4, disposed along the side of the case and the carrying strap.

We claim:

The ornamental design for carrying case for portable hair dryer or the like, as shown and described.
